UNITED STATES PATENT OFFICE.

THOMAS T. PARKER, OF NEW YORK, N. Y.

STEAM-BOILER.

1,259,660.

Specification of Letters Patent. Patented Mar. 19, 1918.

Application filed May 16, 1917. Serial No. 168,937.

To all whom it may concern:

Be it known that I, THOMAS T. PARKER, a citizen of the United States, and resident of the city of New York, in the county of 5 Kings and State of New York, have invented certain new and useful Improvements in Steam-Boilers, of which the following is a specification.

This invention relates to steam-boilers, 10 and particularly to boilers of the "Stirling" type wherein a series of drums arranged in spaced parallel relation to each other are connected by banks of water-tubes through which the water circulation is effected.

15 The object of my invention is to increase the efficiency of a boiler of the character mentioned by effectually separating the greater percentage of the total steam from the circulating water, as rapidly as the 20 steam is generated, and thereupon superheating the separated steam preparatory to its association with the remaining steam, and also is to protect the superheater from the destructive action of the heat from the 25 furnace gases when the boiler is being fired up cold, that is, when the superheater is filled with air.

My invention comprises a transverse drum water-tube boiler having a lower water drum 30 and two upper steam-and-water drums, the latter drum being located at the front and rear respectively of the boiler setting, three banks of water tubes whereof two banks connect the lower drum with the upper 35 drums respectively and whereof the remaining bank connects the two upper drums, and a bank of superheating tubes connecting the upper portions of the two upper drums, said setting having therein a fire box below the 40 forward bank of water tubes, an outlet in rear of the rearward bank of tubes, and a wall located below the bank of connecting water tubes for the upper drums, said wall having an opening therethrough, and a 45 manually-operative damper for said opening, whereby the hot gases in their flow from the fire box to the said outlet can be diverted through a path below the last-named water-tubes, as will be hereinafter described and 50 claimed.

In the drawing—

Figure 1 is a longitudinal vertical section of a water-tube and drum type of steam-boiler embodying my invention.

55 Fig. 2 is a section, enlarged, of a portion

of one of the superheater tubes showing its internal deflecting and protecting member.

Referring to the drawing, 10 designates the boiler setting; 11 the furnace at the lower forward part thereof, and 12 the outlet to the breeching or stack at the rear.

13, 14 and 15 designate the boiler drums; 13 and 14 being the upper steam-and-water drums, and 15 being the lower water or mud drum. The drum 14, which is relatively 65 higher than the other, is provided with a feed-water inlet 16 and with a steam outlet 17.

18 designates the forward bank of tubes connecting the drums 13, 15; 19 the rearward bank of tubes connecting the drums 14, 15, and 20 the upper bank of tubes connecting the drums 13, 14; thereby establishing circulatory communication throughout the 70 drums and tubes.

21, 22 designate the baffles arranged to provide the requisite passes for the gases in their indicated course from the furnace to the breeching.

The steam-space of the drum 13 is connected with the steam-space of the drum 14 by a bank of superheater tubes 23 which are subjected to the action of the heat from the hot gases unless such gases be diverted from their normal course as below explained. 80 The steam as rapidly as it enters the steam-space of the drum 13 passes into the superheater tubes and thence into the steam-space of the drum 14, such steam in its prolonged travel through the tubes thus being effectually dried and superheated by absorption 85 of the heat conducted through the walls of the tubes. By the construction and arrangement described about eighty per cent. of the total steam generated in the boiler enters 90 the superheater tubes and is therein superheated preparatory to its commingling with the remaining steam in the steam-space of the drum 14. The practical importance of 95 this superheating feature is obvious; but, in addition, another important advantage is obtained, namely, by the separation and removal of the steam from the drum 13, the water entering and flowing through the water-tube bank 20 connecting the two upper 100 drums, is "solid," i. e., it contains no entrained steam, and hence the effectiveness of the water heating surface of the said tubes 105 20 is materially increased.

24 designates spirally-twisted strips of 110

sheet metal confined within and extending lengthwise of the superheater tubes, which strips perform the important function of laterally deflecting the steam and causing it to impinge directly against and throughout the inner walls of the tubes as it flows therethrough. Thus the steam absorbs more heat and hence attains higher superheat, and at the same time serves to protect the exposed surface of the tubes from the destructive action of the direct heat from the furnace gases. Each of the strips 24 preferably comprises a series of sections arranged end to end within the superheater tube, the meeting ends of the sections being connected by offset interlocking portions 25, as seen in Fig. 2. Such sectional strips may be applied to the superheater tubes prior to or after the installation of the latter. The ends (26) of the strips are arranged to project slightly into the drum 14 so that such ends may be readily grasped by a suitable tool and thereby forcibly rotated, in which case the strips will effectually scrape the interior of the tubes and expel the contained foreign matter into the drum 14, whence it can be readily removed.

The vertical heat baffle 21, which is located over the bank of tubes 18 nearest the furnace, is provided with a transverse opening 27 equipped with a door 28 which may be opened or closed at will. In the present instance the door is pivotally mounted similarly to a damper, and it is likewise provided with an external operating handle 29.

With water at normal level in the boiler, the furnace fire is started with the door open, as indicated by the dotted lines in the drawing. The hot gases on their way to the stack are diverted through the opening 27 and thus prevented from passing up to and among the superheater tubes, thereby obviating the otherwise liability of burning out the latter. When the steam pressure is raised and the boiler put in service the door 28 is closed. The steam generated in the forward bank of tubes 18 rises to the surface

in drum 13 and flows through the superheater tubes 23 to drum 14. Steam generated in bank 19 flows also into drum 14 and therein commingles with the superheated steam, and absorbs therefrom a portion of the superheat, the entire volume of dry steam thence flowing through the steam outlet 17. The water from drum 14 flows to drum 15 and upward again to drum 13, and so on, thereby establishing a free and unrestricted circulation with a superior superheating effect.

The spiral deflecting and cleaning devices above described form the subject of a divisional application Serial No. 200,276, filed November 5, 1917.

It is to be understood that the details of construction herein disclosed, may be modified within the principle of my invention and the scope of the appended claim.

I claim:

A transverse drum water-tube boiler having a lower water drum and two upper steam-and-water drums, the latter drums being located at the front and rear respectively of the boiler setting, three banks of water tubes whereof two banks connect the lower drum with the upper drums respectively and whereof the remaining bank connects the two upper drums, and a bank of superheating tubes connecting the upper portions of the two upper drums, said setting having therein a fire box below the forward bank of water tubes, an outlet in rear of the rearward bank of water tubes, and a vertical wall located below the bank of connecting water tubes for the two upper drums, said wall having an opening therethrough, and a manually-operative damper for said opening, whereby the hot gases in their flow from the fire box to the said outlet can be diverted through a path below the last-named water-tubes.

Signed at New York, in the county and State of New York, this 14th day of May, A. D. 1917.

THOMAS T. PARKER.
